UNITED STATES PATENT OFFICE

ALEXANDER H. WILSON, OF OAK PARK, ILLINOIS, ASSIGNOR TO THOMAS ELEVATOR COMPANY, OF CHICAGO, ILLINOIS, A CORPORATION OF ILLINOIS

PORTABLE HOISTING MACHINE

Application filed November 18, 1927. Serial No. 234,179.

This invention relates to hoisting machines, having reference more particularly to hoists of a portable character that are adapted to be readily transferred as a unit from one field of operation to another.

One object of the invention is to provide a power hoist of the type specified having a very simple and rugged structure and organization combining a high degree of rigidity and stability with a minimum of weight so that it can readily be drawn by man power, if desired, from place to place. Another object is to provide a construction wherein the weight of the operating parts shall be substantially uniformly distributed on the carrying platform or truck, so as to afford a well balanced portable unit. A further object is to provide an organization wherein the power transmission from the motor to the cable-winding drum shall be located at a low and substantially central point on the carrying platform, thereby reducing to the minimum lateral vibration or side shake when the hoist is in operation.

Still other objects and attendant advantages of the invention will be apparent to persons skilled in the art as the same becomes better understood by reference to the following detailed description, taken in connection with the accompanying drawings showing a practical embodiment of the invention, in which—

Fig. 1 is a side elevation of the complete apparatus, partly broken out;

Fig. 2 is a front elevation, also partly broken out.

By reference to the drawings, it will be seen that the operating parts of the hoist are mounted on a low truck consisting of a skeleton steel platform, and front and rear pairs of supporting wheels. In the very simple structure illustrated, the platform comprises a pair of channel side beams or sills 10 rigidly spaced and connected at front and center by cross-bars 11 and 12. The rear portions of the side beams 10 are spaced and connected by a block 13 that supports the motor hereinafter referred to. To the under sides of the side beams 10 are attached front and rear pairs of journals 14 and 15 for front

and rear axles 16 and 17, on the projecting ends of which axles are journaled the wheels or rollers 18 and 19.

Mounted on, and conveniently cast integral with the cross-bars 11 and 12 are a pair of A-frames 20 and 21, in and between the upper ends of which is journaled a drum shaft 22. Loose on shaft 22 is a winding drum or reel 23 formed at one end thereof with an enlarged head 24 that receives a brake band 25. The outer face of the head 24 is also formed with a conical depression forming a female clutch member 26.

Keyed on the drum shaft 22 adjacent to the head 24 of the drum is a large spur gear 27 having on the side thereof adjacent to the drum a conical male clutch member 28. Loose on the drum shaft 22 opposite the forward end of the drum is a sleeve 29 formed on its forward end with a cam 30 that cooperates with either of a pair of cams 31 formed on a ring 32 attached to the inner side of the upper end of the frame 20. The sleeve 29 has a lateral hollow boss 33 in which is secured a cam operating handle 34. The sleeve 29 abuts at its rear end against the forward end of the drum, and by turning the handle 34 in either direction 90 degrees from the position shown the drum is forced endwise and the clutch members 26 and 28 are engaged, so that the drum is rotated by the gear 27.

Mounted on and rigidly attached to the block 13 is a motor 35, herein shown as an air-cooled internal combustion engine, with the structural details of which the present invention is not concerned. The motor shaft 36 of the engine is drivingly connected preferably by a silent chain 37 and cooperating sprocket wheels with a transmission shaft 38 journaled in bearings 39 formed on the platform cross-bars 11 and 12. Keyed on the shaft 38 is a spur pinion 40 meshing with and driving the large gear 27.

Journalized in and between the side sills 10 of the platform frame is a rock-shaft 41, fast on which, just inside one of the side sills is an arm 42 that is adjustably connected by an eyebolt 43 and pin 44 to one end of the brake band 25, the other end of said band being anchored or dead-ended at 46 to the inner

- side of the other side sill 10. On a projecting end of the rock-shaft 41 is an arm 47, to which is rigidly attached, as by bolts 48, a lever 49 that terminates at its forward end in a pedal 50. On the rear arm of the lever is adjustably secured a weight 51 that normally maintains the pedal lever in the raised position shown in Fig. 1, wherein the brake band is slackened. When the lever 49 is depressed, its forward end snaps beneath a spring catch 52 that is mounted on the outer side of the adjacent sill, said catch serving to hold the depressed lever in a position wherein the brake band is applied to the head of the drum.
- When the brake band is to be released, as the drum clutch is thrown in the lever catch is kicked back, freeing the lever arm, and the counterweight 51 instantly restores the lever to its raised position.
- Pivottally mounted in the forward ends of the side sills 10 is a bail-shaped draft pole 53 by which the machine can be readily hauled to and from its place of operation. When not in use, the pole can be swung upwardly to overlie the forwardly bent upper end of the cam-actuating handle 34.

From the foregoing it will be observed that the drum, the motor, and the transmission mechanism from the motor to the drum are so disposed as to distribute the weight of the parts substantially uniformly from end to end and side to side of the supporting frame, with the axes of the motor and drum shafts disposed in the vertical median longitudinal plane of the truck, whereby any sidewise tipping tendency is eliminated. Furthermore, by locating the transmission shaft through which the drive is transmitted from the motor to the drum at a low point (substantially in the horizontal plane of the truck platform), the transmission thrusts are mostly in a vertical direction and at low points, thereby contributing to the stability of the machine when at work.

I claim—

In a portable hoisting machine, the combination of a platform mounted on wheels, a pair of spaced frames mounted on and crosswise of said platform, a drum shaft journaled in and between said frames in the median vertical longitudinal plane of said platform, a gear keyed to said drum shaft, a hoisting drum loose on said shaft, a motor mounted on said platform in rear of said frames with its shaft axially aligned with said drum shaft, a transmission shaft journaled in said platform beneath said drum, a drive from said motor shaft to said transmission shaft, a pinion on said transmission shaft meshing with said gear, cooperating male and female clutch members on said gear and drum respectively, and manually operable means for engaging said clutch members.
